UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

1,378,947.

Specification of Letters Patent.

Patented May 24, 1921.

Application filed July 14, 1917. Serial No. 180,647.

To all whom it may concern:

Be it known that I, CHARLES L. GOODRUM, a citizen of the United States, residing at New York, in the county of New York and State of New York, have invented certain new and useful Improvements in Machine-Switching Telephone Systems, of which the following is a full, clear, concise, and exact description.

10 This invention relates to machine switching telephone systems, and more particularly to improvements in the operation of line finder switches in such systems.

15 The object of the invention is to provide a common driving mechanism for a plurality of equivalent line finder switches and for allotting an idle line finder switch for use.

20 Generally stated the invention comprises a group of equivalent finder switches of the usual two-motion step-by-step type and a driving mechanism, common to the group, arranged to automatically allot an idle finder switch for use and then to subsequently operate the individual vertical and rotary pawls 25 of such allotted finder to establish a connection with a calling line.

25 In the drawing a diagrammatic view of a structure embodying this invention is shown, together with an indicated calling subscriber's substation and the necessary circuit arrangements for establishing a connection between the calling subscriber's substation and a finder switch.

30 Referring to the drawing, each finder switch comprises a shaft 1 which carries the brushes 2, 3 and 4, the vertical ratchet 5 and the rotary ratchet 6. The brushes are arranged to engage subscribers' line terminals in the terminal bank 8. Each shaft has co-40 operating therewith a vertical pawl 13, a rotary pawl 14 and holding pawls 9 and 10 mounted on an armature 11 of a release magnet 12.

35 The vertical pawls 13 of the finder switches are pivotally mounted on arms 17 which are loosely mounted on a rod 18. The rod is rotatably and longitudinally mounted in a support (not shown) and has spirally arranged thereon a number of cranks 20 each of which 45 is arranged to engage a hole in one of the arms 17. The cranks are so arranged that whenever the rod 18 is in its normal longitudinal position, one of the cranks is in engagement with its associate arm 17 so that if the

50 rod is rotated, the vertical pawl attached to the engaged arm 17 is operated to raise the shaft of its associated switch. In order to allow another switch to be operated by the rod 18, the rod is first moved longitudinally to the left (as viewed in the drawing) by the 55 attraction of the armature of magnet 42. This movement of the rod is sufficient to move the cranks away from the arms 17 which do not move with the rod when it is moved longitudinally. The rod 18 is then 60 rotated without operating any of the arms 17 until a desired position is reached, at which time the magnet 42 becomes deenergized and the proper crank 20 engages the arm 17 of the proper switch so that subsequent rotation of the rod will operate this allotted switch.

65 The rod 18 has fastened thereto a ratchet wheel 21 which is engaged by a pawl 22 attached to the armature of a magnet 23. At 70 the opposite end of the rod 18 another ratchet wheel 25 is loosely mounted in such a manner that it is free to rotate on the rod, but it moves longitudinally with the rod. Normally this ratchet wheel is engaged by a holding pawl 76, which is mounted on the frame (not shown), to prevent the wheel from rotating in a counter-clockwise direction. The 75 ratchet wheel 25 is also normally engaged by an operating pawl 24 fastened to a collar 77 which is mounted on the rod in such a manner that it rotates with the rod, but does not move longitudinally therewith. By this arrangement it will be seen that during the vertical operation of a finder switch the ratchet 80 wheel 25 will be rotated in a clockwise direction by the pawl 24. But as soon as the rod 18 is moved longitudinally the ratchet wheel 85 disengages the pawls 24 and 76, the ratchet wheel is returned to its normal position by a 90 spring 26, one end of which is fastened to the ratchet wheel 25 and the other end is fastened to the frame (not shown). This spring also 95 serves to hold the rod 18 in its normal longitudinal position.

100 A brush 27 is insulatedly mounted on the ratchet wheel 25, and serves to hold the wheel in its normal position and also to keep spring 28 from engagement with spring 29 by normally engaging the spring 28. During the 105 rotation of the wheel by the pawl 24, the brush engages contacts 30 for a purpose hereinafter described.

The rotary pawls 14 of the switches are mounted on the arms 31 which are pivoted on a support (not shown). Each arm 31 has a lug 32 which projects downward and which is arranged to be engaged by a pair of pins 33 and 34 carried by a rod 35. These pairs of pins are spirally arranged on the rod 35 in such a manner that only one arm 31 at a time is capable of being operated by the longitudinal movement of the rod 35. The rod 35 carries a brush 36 which engages contacts 37 when the rod is rotated by a magnet 38 whose armature carries a pawl 102 which engages a ratchet wheel 39 on the rod. In order to maintain the proper relation between the shafts 18 and 35 so that the vertical and rotary pawls of the same finder switch will be selected and operated, the two shafts are connected together by the gears 40 and 41.

It is believed that the invention will now be more readily understood by tracing a connection between a calling subscriber at substation A and a finder switch. It will be assumed that the apparatus is normally in the condition shown in the drawing, namely, the finder switch at the left of the drawing is the one allotted for use.

When the subscriber at substation A removes his receiver from the hook a circuit is completed from grounded battery, right-hand winding of relay 50, inner left-hand armature and back contact of relay 51, line conductor 52, telephone apparatus of substation A, line conductor 53, back contact and outer left-hand armature of relay 51, left-hand winding of relay 50 to ground. Relay 50 then becomes energized and completes a circuit from grounded battery, winding of relay 54, left-hand armature and back contact of relay 55, conductor 56, contact spring 57 and its back contact 58, conductor 59, contact spring 60, left-hand armature and front contact of relay 50, back contact and outer left-hand armature of relay 51, left-hand winding of relay 50 to ground. Relay 54 becomes energized and at its left-hand armature and front contact completes a locking circuit for itself to conductor 56 and ground over the circuit previously described. Relay 54 at its outer right-hand armature and front contact connects ground to contact 30, which is individual to the group of lines with which the calling line is associated. At its inner right-hand armature and front contact, relay 54 completes a circuit from grounded battery, winding of relay 55, front contact and inner armature of relay 54 to ground. Relay 55 becomes energized and connects ground at its right-hand armature and front contact to conductor 61. This connection of ground to conductor 61 completes a circuit from grounded battery, winding of relay 72, back contact and right-hand armature of relay 70, conductor 71 to ground

over conductor 61. Relay 72 by attracting its armature produces a break in the energizing circuit of the release magnet 12. The grounding of conductor 61 also completes a circuit from grounded battery, winding of relay 65, conductor 64, contact springs 63 and 62 to ground over conductor 61. The energization of relay 65 establishes a break in conductor 78. A circuit is also completed at this time from grounded battery, winding of primary magnet 23, contact springs 69 and 68, conductor 67, side-switch arm 66, contact springs 63 and 62 to ground over conductor 61. Primary magnet 23 by attracting its armature rotates the rod 18, thereby causing the arm 17 of the allotted switch to move the pawl 13 into engagement with the vertical ratchet 5. The shaft 1 is thereby moved upward so that the brushes 2, 3 and 4 are placed in operative relation to the first group of contacts in the bank 8. Only a slight rotation of the rod 18 is produced due to the arm 17 engaging the stop 79, but this rotation is sufficient to move the brush 27 into engagement with the first contact 30, in which position it is held by the pawl 76 engaging the ratchet wheel 25. As soon as primary magnet 23 deenergizes the rod 18 is returned to its normal position by spring 15 fastened to arm 17. Since primary magnet 23 opens contact springs 68 and 69 each time it is energized, a stepping circuit is produced, thereby causing the brush shaft 1 to be moved upward step by step over the various groups. This vertical movement of brush shaft 1 continues until the brush 27 engages the contact 30 individual to the group with which the calling line is associated. A circuit is then completed from grounded battery, winding of escape magnet 73, side-switch arm 74, conductor 75, brush 27, contact 30, front contact and outer right-hand armature of relay 54 to ground. Escape magnet 73 becomes energized and moves the side-switch arms into position 2. The escape magnet being slow to release is held energized until a circuit is closed therefor when the side-switch arm 74 reaches its second position: from grounded battery, winding of escape magnet 73, side-switch arm 74 in second position, side-switch arm 66 in second position, contact springs 63 and 62 to ground over conductor 61. An energizing circuit is closed for secondary magnet 87 grounded battery, winding of magnet 87, contact springs 84 and 85, conductor 86, side-switch arm 66, contact springs 63 and 62 to ground over conductor 61.

The secondary magnet 87 by attracting its armature moves the rod 35 longitudinally, thereby causing the arm 31 and the pawl 14 of the allotted switch to be operated to rotate the shaft 1 so that the brushes 2, 3 and 4 engage the first set of contacts in the

selected group. As soon as the secondary magnet becomes deenergized the rod 35 is returned to its normal longitudinal position by spring 96. The secondary magnet by attracting its armature opens contact springs 84 and 85. Thus it is intermittently energized and deenergized to move the brushes 2, 3 and 4 step by step from one set of contacts to the next until the terminals of the calling line are reached, at which time a circuit is completed from grounded battery, winding of cut-off relay 51, conductor 88, terminal 97 test brush 4, side-switch arm 90 (second position) to ground. Relay 51 becomes energized and by attracting its armature causes the deenergization of line relay 50, which in turn causes the deenergization of relay 54. The retraction of the inner armature of relay 54 removes ground from conductor 61 and thereby causes the deenergization of relay 65, relay 72, secondary magnet 87 and escape magnet 73. The deenergization of relay 73 causes the side-switch arms to move into position 3. The deenergization of relay 65 closes the break in conductor 78 to complete a circuit from grounded battery, left-hand winding of magnet 42, conductor 100, armature and back contact of relay 65, conductor 78, brush 36, contact 37, conductor 104, contact springs 95 and 96 (closed upon the first vertical step of the shaft 1) to ground. Magnet 42 by attracting its armature moves rod 18 longitudinally, thereby moving the crank 20 out of engagement with arm 17 of the last used switch, and also ratchet wheel 25 out of engagement with pawls 24 and 76. The ratchet wheel is then returned to its normal position by spring 26. In order to assure the ratchet wheel 25 reaching its normal position before magnet 42 deenergizes, a locking circuit for magnet 42 is completed from grounded battery, right-hand winding of magnet 42, contact springs 105 and 106, conductor 107, contact springs 28 and 29 to ground. As soon as the ratchet wheel reaches its normal position, brush 28 separates contact springs 28 and 29 and opens this locking circuit.

50 The deenergization of relay 65 also completes a circuit from grounded battery, winding of allotter magnet 38, contact springs 80 and 81, conductor 83, armature and back contact of relay 65 and conductor 78, brush 36, contact 37, conductor 104, contact springs 95 and 96 to ground. Magnet 38 becomes energized and by operating pawl 102 rotates the rods 35 and 18 so that they are in a position to operate the next finder switch, but 60 if this finder switch is busy, ground will be found upon terminal 37 associated therewith, which will cause the magnet 38 to again energize and rotate the rods 18 and 35 another step. This rotation continues 65 until brush 36 engages a contact 37 which

is not grounded, at which time magnets 42 and 38 then become deenergized. Magnet 42 is made slow to release its armature, and therefore it remains attracted during this rotation of the rod. The retraction of the armature of magnet 42 causes the crank 20, associated with the next allotted finder, to engage the arm 17, so that when the rod 18 is rotated the shaft 1 of this allotted finder will be operated. 75

When the brushes 2 and 3 of the finder switch engage terminals 99 and 98 of the calling line and the side switch moves into position 3, a circuit is completed from grounded battery, right-hand winding of relay 70, side-switch arm 105 (third position), conductor 92, brush 3, terminal 98, line conductor 52, telephone apparatus of substation A, conductor 53, terminal 99, brush 2, conductor 91, side-switch arm 104 80 (third position), left-hand winding of relay 70 to ground. Relay 70 becomes energized and completes a circuit from grounded battery, winding of relay 93, front contact and left-hand armature of relay 70, conductor 90 94, contact springs 95 and 96 to ground. Since relay 72 is slow releasing, the energizing circuit of the release magnet 12 will be opened at the back contact and left-hand armature of relay 93 before it is closed by 95 the deenergization of the relay 72.

The releasing of the operated finder switch is as follows: When the calling subscriber at substation A replaces his receiver the circuit of relay 70 is opened, which 100 causes the deenergization of relay 93. A circuit is then completed from grounded battery, winding of release magnet 12, conductor 109, armature and back contact of relay 72, armature and back contact of relay 93, 105 left-hand armature and back contact of relay 70, conductor 94, contact springs 95 and 96 to ground. Release magnet 12 by attracting its left-hand armature completes a locking circuit for itself from battery, winding of release magnet 12, front contact and left-hand armature of this relay, conductor 94, contact springs 95 and 96 to ground. Release magnet 12 by attracting its right-hand armature removes the vertical holding pawl 115 9 from the ratchet 5 and the rotary pawl 10 from the rotary ratchet 6, thereby allowing the shaft 1 to return to its normal position, at which time the locking circuit of relay 12 is opened at contact springs 95 120 and 96.

What is claimed is:

1. In a telephone exchange system, the combination with a plurality of contact banks, a movable shaft individual to each bank, brushes mounted on each shaft and arranged to engage contacts of said contact banks, a common driving rod for moving said shafts in one direction, a common driving rod for moving said shafts in a sec- 130

ond direction, means for placing said common rods in operative relation to an idle shaft, and means for operating said rods individually to move the brushes of said selected shaft into engagement with any contact of said contact banks.

2. In a telephone exchange system, the combination with a plurality of movable shafts, a common driving rod for moving 10 said shafts vertically, a common driving rod for rotating said shafts, means for operating said rods together to position them in operative relation to any one of said shafts, means for operating said first mentioned 15 common driving rod to raise the selected shaft, and means for subsequently operating said second common driving rod to rotate said selected shaft.

3. In a telephone exchange system, the 20 combination with a plurality of movable shafts, a common driving rod for moving said shafts vertically, a common driving rod for rotating said shafts, means for rotating said rods together to position them in operative relation to any one of said shafts, 25 means for rotating said first mentioned common driving rod to raise the selected shaft, and means for subsequently moving said second mentioned common driving rod longitudinally to rotate said selected shaft.

4. In a telephone system, the combination 30 of a plurality of contact banks, a movable shaft for each bank, a driving mechanism common to said shafts, means for operating said mechanism step-by-step to drive said shafts in one direction, means for operating said mechanism step-by-step to drive said shafts in a second direction, and brushes carried by said shafts arranged to coöperate 40 with the contact banks.

5. In a telephone system, the combination 45 of a plurality of contact banks, a movable shaft for each bank, a driving mechanism common to said shafts, means for operating said mechanism step-by-step to drive said shafts vertically, means for operating said mechanism step-by-step to rotate said shafts, and brushes carried by each shaft arranged to coöperate with the contact banks.

50 6. In a telephone system, the combination 55 of a plurality of contact banks, a movable shaft for each bank provided with a set of brushes, a common driving mechanism for said shafts, means for allotting said mechanism to one of said shafts, and means for operating the mechanism step-by-step to drive the brushes of the allotted shaft in two different planes into engagement with the contacts of the bank.

60 7. In a telephone system, the combination 65 of a plurality of contact banks, a movable shaft for each bank provided with a set of brushes, a common driving mechanism for said shafts, means for allotting said mechanism to one of said shafts, and

means for operating the mechanism step-by-step to drive the brushes of the allotted shaft in two planes at right angles to each other for engaging the contacts of the individual contact bank.

70 8. In a telephone exchange system, the combination with a plurality of contact banks, a movable shaft individual to each bank, brushes mounted on said shaft and arranged to engage contacts of said contact bank, a common driving mechanism for selecting and lifting and rotating any one of said shafts, whereby the brushes of said selected shaft are moved into engagement with any contact of said contact banks.

75 9. In a telephone exchange system, the combination with a plurality of contact banks, a movable shaft individual to each bank, brushes mounted on each shaft and arranged to engage contacts of said contact banks, a common driving mechanism for lifting and rotating any one of said shafts, and means for placing said driving mechanism into operative relation to an idle shaft, whereby the brushes of said selected shaft are moved into engagement with any contact of said contact banks.

80 10. In a telephone exchange system, the combination with a plurality of contact banks, contacts movable in two directions 95 at right angles to each other, said movable contacts individual to each bank and arranged to engage the contacts thereof, mechanical driving means common to said movable contacts and adapted to automatically select and operate any one of said movable contacts individually.

100 11. In a telephone exchange system, the combination with a plurality of contact banks, contacts movable in two planes, said contacts individual to each bank and arranged to engage the contacts thereof, driving means common to said movable contacts and adapted to automatically select and operate any one of the movable contacts individually.

105 12. In a telephone exchange system, the combination with a plurality of contact banks, contacts movable in two planes and at right angles to each other, said contacts individual to each bank and arranged to engage the contacts thereof, mechanical driving means common to said movable contacts and adapted to automatically select and operate any one of said movable contacts individually.

110 13. In a telephone system, the combination 115 of a plurality of contact banks, a movable shaft individual to each bank, a step-by-step operated rod common to said shafts for operating them in a first movement, a step-by-step operated rod common to said shafts for operating them in a second movement, and brushes carried by each shaft for engaging said contact banks.

14. In a telephone system, the combination of a plurality of contact banks, a movable shaft for each contact bank, a rod common to said shafts, means for rotating said 5 rod step-by-step to drive said shafts in a first movement, a second rod common to the movable shafts, means for operating said second rod longitudinally in a step-by-step manner to drive said shafts in a second 10 movement, and brushes carried on said shafts for engagement with the contact banks.
15. In a telephone exchange system, the combination with a plurality of contact 15 banks, a movable shaft individual to each bank, brushes mounted on each shaft and arranged to engage contacts of said contact banks, a common driving mechanism for moving said shaft in one direction, a common driving mechanism for moving said shaft in a second direction, means for placing 20 said common driving mechanisms in op-
- erative relation to an idle shaft, whereby the brushes of said selected shaft are moved into engagement with any contact of said contact banks. 25
16. In a telephone system, the combination of a plurality of contact banks, a movable shaft for each contact bank, a member common to all said shafts, means for operating said member in a step-by-step movement to select one of the movable shafts, means for operating said member in a rotary step-by-step movement to drive the selected shaft in its first movement, means 30 for operating said member in a longitudinal step-by-step movement to drive said shaft in its second movement, and brushes carried by each shaft for engagement with the contact banks. 35
- 40

In witness whereof I hereunto subscribe my name this 13th day of July, A. D. 1917.

CHARLES L. GOODRUM.
